ATTORNEY

UNITED STATES PATENT OFFICE.

CHARLES KITSCHELT, OF NEW YORK, N. Y., ASSIGNOR TO NICHOLAS MULLER'S SONS & CO., OF SAME PLACE.

DESIGN FOR A MATCH-BOX.

SPECIFICATION forming part of Design No. 11,863, dated July 13, 1880.

Application filed May 8, 1880. Term of patent 3½ years.

To all whom it may concern:

Be it known that I, CHARLES KITSCHELT, of the city, county, and State of New York, have invented a new and original Design for 5 Match-Boxes, of which the following is a full, clear, and exact description.

The nature of my design is fully shown in the accompanying drawings, to which reference is made, and in which—

10 Figure 1 is a perspective view, and Fig. 2 a vertical transverse section, of my improved match-box.

Similar letters of reference indicate corresponding parts.

15 This invention relates to an improved design for match-boxes of that class in which a weighted and fulcrumed body with one or more pointed pins at its upper end is employed for picking up the matches which are placed 20 into the body of the box; and the invention consists of an exterior supporting-case formed of a slightly conical trunk and a top plate, in connection with a hinged bird applied to an abutment at the rear portion of the exterior 25 case.

In the drawings, A represents the outer supporting-frame of the match-box, which is

provided with a concave base, a, which may be ribbed or otherwise ornamented, of a slightly conical and ornamental middle portion, b, 30 and of a slightly projecting top plate, d.

To a plain abutment, e, at the rear part of the supporting-frame A, is hinged a weighted body, B, in the shape of a bird, the upper end or beak of which terminates in one or two 35 sharp points.

Having thus described my invention, I claim as new and desire to secure by Letters Patent—

The design for a match-box, consisting of a 40 supporting-frame, A, formed of a concave base, a, a tapering trunk, b, a top plate, d, and a plain abutment at the rear, and of a bird, B, supported on the abutment, substantially as described, and shown in the accompanying drawings.

In testimony that I claim the foregoing as my invention I have signed it this 31st day of March, 1880.

CHARLES KITSCHELT.
